UNITED STATES PATENT OFFICE

EDWARD S. SHEPERD, OF ST. JOSEPH, MISSOURI, ASSIGNOR TO ALBERT D. STEWART, OF ST. JOSEPH, MISSOURI

PROCESS AND APPARATUS FOR PRODUCING FELTED FIBROUS BOARD

Application filed September 6, 1928. Serial No. 304,254.

The present invention relates more particularly to a process and apparatus especially designed for producing a felted fibrous board from cereal straw fibers.

5 In recent years there has been developed a number of types of boards having thicknesses of approximately $\frac{3}{8}$ " to $\frac{1}{2}$ ", particularly adapted for insulating and sound deadening purposes. Some of these boards belong to 10 that class which can be used as substitutes for lumber, that is, they have the necessary inherent structural rigidity and stiffness to permit substitution thereof for lumber. It is in this class of board that the board product 15 of the present invention is classified.

Attempts have been made heretofore to utilize cereal straw as the fiber for making such a board. Cereal straw fibers, such as rice straw and wheat straw, have been used.

20 The present invention, in the described embodiment thereof, deals with wheat straw fibers specifically, although in its broader aspects the process and apparatus have been designed to efficiently work on the other 25 classes of cereal straw.

Among the salient objects of the invention are to provide an apparatus making use of two rotatable felting cylinders, one preferably disposed on a plane slightly lower than the other; to provide an apparatus so designed as to continuously produce a board of uniform characteristics; to provide an apparatus comprising two rotatable felting cylinders disposed above, and in communication with 25 a specially designed forming or pulp suspension receiving chamber, characterized in that the latter is located substantially centrally between the two forming cylinders so that the board as felted or formed passes upwardly between the two cylinders, to which latter pressure is applied to secure the necessary extraction of water to produce a board sufficiently dry to allow its transfer to a carrying belt or other instrumentality leading to the 40 press and drying parts of the machine; to provide an apparatus by which the board may be produced as a continuous sheet; to provide in a construction of the character described stationary end seals attached to 45 said forming chamber to effectively prevent 50 leakage of the pulp solution; to provide seals between the ends of the two cylinders and the ends of the adjacent forming chamber by providing grooves in each end of each forming cylinder disposed oppositely to each 55 other, in which the edges of the seals ride; to provide a stationary seal effectively performing its sealing function regardless of the rotation or lateral movement of the two felting cylinders; to provide a stationary seal of 60 the character described capable of automatically adjusting itself to all positions of the two cylinders; to provide in a construction of the character described separate, independently controlled inlets for the admission 65 of the pulp solution to the forming chamber; to provide in a construction of the character last described a bottom inlet preferably located at the extreme bottom of the forming chamber, and an upper inlet located adjacent 70 the upper end of the forming chamber as near as possible to the point where the sheets formed on the two cylinders meet and are united into a single sheet of board; to provide in a construction of the character 75 described a specially designed lower inlet comprising a plurality of abutting freely communicating chambers, each having an inlet disposed centrally thereof and at the low point of each chamber, the lower surfaces 80 of the chamber from the center inlet tapering upwardly to the ends to form a progressively increasingly restricted passageway; to provide in a construction of the character last described a longitudinal opening in the upper 85 edge of each chamber discharging the pulp solution into the forming chamber proper; to provide in a construction of the character described an upper inlet disposed within the forming chamber and preferably taking the 90 form of an elongated oval, the upper edge thereof being provided with a longitudinal opening through which the pulp solution fed thereto discharges into the forming chamber at a point where the sheets carried by the 95 two cylinders come together; to provide in combination with the construction described means for separately charging said lower inlet and said upper inlet; to provide in a construction of the character described longi- 100

tudinal seals disposed between the upper outer longitudinal edges of the forming chamber and the adjacent cylinder to prevent leakage of the pulp solution at that point; to provide a machine designed to operate efficiently and effectively with a minimum of mechanical working parts; to provide a machine in which repair and replacement can be made very quickly and very easily; to provide a process wherein the thickness of the board being made is controlled by controlling the consistency and amount of stock fed through the lower inlet and the upper inlet to the forming chamber; to provide a process in which all of the pulp may be fed in suspension to the lower inlet while clear water or pulp suspension of different consistency or different character can be fed through the upper inlet; to provide a process and apparatus in which the forming of the sheet on the felting cylinders takes place under the influence of the hydrostatic head pressure of the liquid charged to the lower and upper inlets of the forming chamber; to provide a process and apparatus in which the water removed during the forming operation flows through each cylinder and discharges beyond said longitudinal seals, washing the surfaces of said cylinders to remove pulp carried thereon, thus eliminating the necessity for using auxiliary showers for this purpose, while at the same time being discharged at a point away from the point where such water might tend to back up on the sheet already formed and re-float the fibres; to provide an apparatus in which all flow pipes from the head box to the forming chamber are so designed as to maintain a uniform flow of pulp suspension from the time it leaves the head box until it reaches the forming wire; to provide a process and apparatus in which the amount of water contained in the board after it is stripped from the lower forming cylinder is regulated entirely by the extent of pressure applied by the two forming cylinders against the board as the two sheets are being united and passing between said cylinders; to provide an apparatus in which the distance between the two cylinders may be varied; and in general to provide an improved process and apparatus of the character referred to.

In the drawings, Fig. 1 is a side elevational view of the apparatus of the present invention.

Fig. 2 is an enlarged end elevational view of the two felting cylinders illustrating the mechanism for adjusting the position of one cylinder relative to the other.

Fig. 14 is a cross sectional view taken on line 14—14 of Fig. 13.

Referring more in detail to the drawings, clear water is fed under suitable pump pressure through either or both of the inlets 1 to a water reservoir 2. The water tank 2 is disposed at a considerable height preferably immediately below the ceiling or roof of the building in which the apparatus is located, and is provided with two separate draw-offs 3 and 3', controlled respectively by valves 4 and 4'. Each of the pipes 3 and 3' discharges into a larger pipe 5 and 5'. The pipes 5 and 5' are disposed at the base of a head box 6.

The design of this head box is peculiar to the apparatus of the present invention and in its preferred form, is divided longitudinally by means of baffles 7 and 7' into three longitudinal compartments 8, 8' and 8". The arrangement is such that straw pulp in suspension after having been suitably shredded, beaten and washed is forced from the usual stuff chest through the pipe 9 into the compartment 8, flowing therethrough in such a manner that said straw pulp suspension is maintained in motion, the excess not used being returned through the overflow pipe 10 to the stuff chest.

Each of the partitions 7 and 7' is provided with a gate valve 11 and 11', respectively, for a purpose to be hereinafter described. An inlet 9' communicates with the compartment 120

8' whereby the latter may be charged with straw pulp suspension of the same consistency as the suspension fed to the compartment 8 or of a different consistency, or of a different character of fiber. For instance, it may be desirable to incorporate with the straw fiber a small quantity of paper fibers, such, for instance, as news print or the like. For this purpose, the character of fiber as well as the consistency thereof may be accurately controlled by controlling the material fed through the pipe 9' into the compartment 8'. By proper manipulation of the gate valves 11 and 11' a regulated quantity of the pulp suspension fed to the compartments 8 and 8' may flow into the mixing compartment 8'', wherein admixture takes place between the fibers in each of the suspensions, being removed from the compartment 8'' through the discharge pipe 5.

As heretofore described, the water charging pipe 3 discharges directly into the pipe 5 and acts to dilute the pulp suspension to the consistency desired, and since this water is under some head, it will discharge with more force into the pipe 5 than the pulp solution flowing thereto, acting in effect to break up any clots of fibers which might have formed due to stagnation, thus causing said fibers to again float as separate fibers in the water. The compartment 8' is provided with an overflow 10' functioning similar to the overflow 10 previously described.

As a feature of the present invention, the compartment 8' is divided transversely by means of a partition 12 to provide a compartment 12'. The partitions 7 and 7' forming the compartment 12' may be provided with gate valves 13 and 13' similar to the gate valves 11 and 11', the arrangement being such that regulated quantities of the pulp suspension flowing in the compartments 8 and 8' may be fed into the compartment 12' for a purpose to be hereinafter described.

The pipes 5 and 5' discharge into the conventional flow box 13^a provided with the baffles 14 alternately disposed to impart an up and down flow to the pulp suspension. In the present instance the flow box 13^a may be divided transversely by means of the partition 15 into two compartments 16 and 16'. The pipe 5 discharges into the compartment 16 while the pipe 5' discharges into the compartment 16'. The pulp suspension flowing over the last baffle in the compartment 16 may be removed therefrom through the enlarged outlet 17, while the liquid leaving the last baffle in the compartment 16' discharges through the pipe 17'.

The amount of water contained in the pulp suspension is carefully predetermined and controlled so as to control the thickness and amount of fiber in the finished dry board. For this purpose, the reservoir 2 may be provided with a water overflow 2' whereby ex-

cess water may overflow and a constant head maintained.

The water reservoir 2 is supported on the frame 18, which in turn may be supported on the perch 19 supported on the supporting structure 20 which also supports the flow box 13^a. The perch 19 is made exceptionally large to permit an operator to move around thereon for adjustment of the gates and valves heretofore described to vary the thickness or weight of board in the finished product.

The discharge 17 terminates in a plurality of branches 21 of similar size, each of which communicates with the center of a chamber 22. There may be a number of these chambers 22 disposed in abutting freely communicating relation to each other, each chamber being supported as illustrated at 23; 24 illustrating the floor.

As a feature of the invention, each of the chambers 22 is of a particular design, the inlet 21 being disposed centrally of each chamber 22 and at the lowest point in the chamber. From the center opening 21 each side of each chamber tapers upwardly, as illustrated, at 25 (Fig. 4) toward its end. Each chamber preferably comprises two halves united by means of bolts, rivets or other suitable locking elements registering with the holes 26 provided for that purpose, and in cross sectional view each complete chamber takes the form of an oval of greater area at its center and decreasing in area toward each end from the center.

Pulp suspension fed through each of the branches 21 to each of the chambers 22 is caused to have a uniform flow and circulation in the chamber 22 due to its construction. This is obvious, since at the point of introduction of the pulp suspension into each of the chambers 22, each chamber has the greatest area and decreases in area from this point toward each end. This avoids any danger of

dead spots or accumulations of fiber which would result in clogs or slugs of the fiber passing through the machine intermittently. The final discharge from each of said chambers 22 into the forming chamber 27 is through a perfect machined longitudinal opening or slot 28 (Fig. 5) about $3\frac{1}{4}$ " to $1\frac{1}{4}$ " wide, more or less, in the upper portion thereof, insuring an absolutely uniform discharge of the pulp solution over the entire width of the forming chamber and from the latter onto the forming area of the two felting cylinders 29 and 29', resulting in a uniformly formed sheet of board on each cylinder as regards thickness and formation.

The specific design of the forming chamber 27 tends to carry the fibers entering through the bottom inlets 21 and 28 directly to the wire covered surfaces of the two cylinders as these surfaces enter the forming chamber past the longitudinal seals 30, thus forming

the two outer surfaces of the board of the particular fiber that is fed into the machine through the bottom inlet 21. All flow pipes leading from the water reservoir 2 and head box 6 are so designed as to maintain a uniform flow of pulp solution from the time it leaves the flow box until it reaches the forming wire.

Each of the forming cylinders comprises a central supporting shaft 31 and 31' on which are securely mounted a number of cast steel spiders 32 specially designed to receive on their outside rim a series of longitudinally disposed heavy wooden bars 33 arranged parallel with the supporting shafts 31 and 31', these bars being arranged with open spaces (1/2" to 1 1/2" apart) between them to permit free and unrestricted passage of water during the process of formation of the desired sheet of board. Over these wooden bars or slats a heavy bronze or other heavy metal wire 34 is wound, preferably spirally, from end to end of the cylinder as a foundation to receive a covering of one or more plies of metal cloth or screening 35 applied to complete a suitable forming surface for proper felting of the board.

The cylinders 29 and 29' are mounted on suitable supporting frames 36 and 36', respectively, on which are mounted bearings 37 and 37', respectively. The bearings 37 may be stationary, while the bearings 37' for the cylinder 29' may be adjustable in the direction of the stationary cylinder 29 to allow for adjustment of pressure to remove the necessary amount of water from the formed sheet of board. These means for adjustment will be hereinafter more particularly described.

The two cylinders 29 and 29' are geared together by means of the gears 38 and 38' to insure uniform rotation as regards each other. Power may be transmitted to the gear 38 and from the latter in turn to the gear 38' through the pinion gear 39 mounted on shaft 40, which in turn carries a large gear 41 meshing with a spur gear 42 mounted on shaft 43 and receiving rotation from the pulley 44 and belt 45. The forming chamber 27 is located substantially centrally between the two forming cylinders 29 and 29' to which pressure is applied toward each other to secure the necessary extraction of water to produce a board sufficiently dry to allow its transfer to the carrying belt 46 leading to the press and drying parts of the machine.

Returning now to the lower inlet 21, and the outlet 28 therefrom into the forming chamber, the pulp suspension fed therethrough will be forced to the surface of each of the slowly rotating cylinders 29 and 29' and due to the hydrostatic head maintained on said pulp suspension the water will pass directly through each cylinder, discharging on the opposite side thereof just beyond the

longitudinal seals 30 in such a manner as to wash such surfaces free of any pulp carried thereon. This latter step is important, since it eliminates the necessity for using a shower usually employed for the purpose of cleaning the cylinder walls. It is also important at this point to note that the water is removed at a point where it will not flow back on the board being formed, which would result in breaking the bond between the fibers and restore them to a condition of flotation in a water vehicle. This is one of the objections to many of the apparatus now in general use for the production of a board of the character produced by my machine.

The longitudinal seal 30 is provided on each of the opposite outer edges of the forming chamber 27 and comprises rubber or the like contacting the faces of the screen and sealing against any leakage at that point. The seal may be fastened to the angle iron upper edge of the forming chamber 27 by any suitable means, such, for instance, as a clamp bolted thereto.

Referring now to another feature of the present invention, the upper inlet 47 is charged from both ends through the branches 48 and takes the form of an oval shaped pipe, provided on its upper surface with a narrow longitudinal continuous slot 49 approximately 1/2" to 1 1/4" wide, more or less. In the use of the top inlet in the present apparatus, I introduce clear water or a solution of water and pulp of any consistency or nature at the point where it is possible to set up a counter flow action in the forming chamber, thus causing a mild disturbance at that point, which results in a more perfect formation and felting of individual fibers, insuring the strongest, and at the same time the lightest weight board for a given thickness. This inlet also permits the insertion of fiber of an entirely different composition and nature relative to that already formed on the cylinders from the pulp solution admitted through the bottom inlet, giving a control over the lamination and interior structure of the board superior to that which can be obtained in any other process of formation of which I am aware.

As has been explained, the purpose of using the upper inlet 47 is to maintain at the point where the two sheets are coming together a circulation of liquid and proper consistency of stock in suspension so as to result in the two sheets interlocking and felting together to produce one sheet in which the fibers are intimately interlaced and felted in such a manner as to prevent delamination.

Referring now to another feature of the present invention, I make use of a stationary end seal 50 disposed on each end of the machine. This seal 50, which may be made of rubber or metal and may be either flexible or unflexible, generally takes the form of an

inverted Y (Figs. 5 and 6), the stem of the Y terminating at a point disposed slightly above the upper contacting point between the two forming cylinders. One of these seals is disposed on each end of the cylinders and is adapted to register with the cylinders, through the medium of opposed annular grooves 51 in the cylinders, thus preventing any water or pulp from leaking beyond the ends of the cylinders. The grooves 51 may be formed by placing annular rings on the ends of the cylinders a sufficient distance away from such ends and at a depth of approximately 1½" to 2" more or less to accommodate the seal. These seals may be held securely in place against the end walls 52 of the forming chamber by means of clamps or other suitable locking elements 52' and bolts or other locking elements 53' passing through the holes 53 in the end wall 52 and seal 50, thus holding the seals securely in registration with the grooves adjacent the ends of the cylinders. Due to the fact that each groove is from 1½" to 2" deep, more or less, and furthermore, since the edges of the seal register in said grooves to the greatest possible extent when the cylinders are close together, it is obvious that the movable cylinders can be adjusted within a latitude up to 1¾" and yet have the seals automatically accommodate themselves to such movement. Yet, the seal is simple in construction and efficient in use.

In Fig. 11 I have attempted to diagrammatically illustrate the manner in which the fibers form on each of the cylinders 29 and 29' and the manner in which the two sheets thus formed come together and are united and interlocked to form a single unitary sheet 54 which is taken on the forming cylinder 29' and passed to the receiving belt 46. It is to be understood that this is merely diagrammatic for the purpose of a clear understanding of the invention. The branches 48 communicate with opposite ends of the upper conduit 47 through the walls of the end closures 52 of the forming chamber.

The supporting frames 36 and 36' are connected together by means of an adjustable screw bolt 55. As heretofore stated the bearing 37 is a stationary bearing, while the bearing 37' is movable. A yoke 56 is mounted on the supporting structure 36'. A movable arm 57 depends from the center of said yoke 56, being pivoted at 58. The arm 57 carries the bearing 37', thus permitting said bearing to be moved back and forth and with it the cylinder 29'. The positioning of the movable bearing is regulated by obvious manipulation of the adjusting screw 59 against the tension of the coil spring 60, said spring functioning to press the cylinder 29 against the board passing between the two cylinders.

The operation should be apparent from the foregoing description. In starting the machine, power is transmitted through the belt

45 and pulley 44 to the gears 38 and 38' whereby the forming cylinders 29 and 29' are slowly rotated, the cylinder 29 in a clockwise direction and the cylinder 29' in a counter-clockwise direction. The proper amount of water is constantly charged to the reservoir 2 so as to maintain at all times a predetermined head as well as a predetermined volume of water. Pulp solution is constantly fed to the compartment 8 and to the compartment 8' if desired, passing from said compartment or compartments into the mixing compartment 8" wherein water is added and from there through the pipe 5, and flow box 13^a into the lower inlets 21 and through the opening 28 in chambers 22 into the forming chamber 27.

In case the consistency and amount of stock contained in the suspension fed through the opening 28 into the forming chamber 27 is sufficient, relative to the speed of rotation of the forming cylinders 29 and 29' to produce a board of the desired thickness and weight, clear water may be charged to the compartment 12' through the pipe 3', passing through the pipe 5', compartment 16' of the flow tank 13^a, branches 48 into the upper inlet 47, through the mouth 49 and charged immediately adjacent the point at which the two sheets forming on the cylinders 29 and 29' come together. In the same manner, should it be desired to incorporate stock in the chamber 12', this can be done by proper manipulation of the gates 13 and 13', in which event a thin suspension may be projected through the mouth 49 instead of clear water. The adhesive qualities of news print and similar paper pulp is well known, and advantage might be taken of this fact to project such type of pulp directly into the nip at the point where the two sheets are coming together to insure an effective interlocking at that point and the production of a homogeneous sheet.

The seals 50 will function to effectively prevent leakage past the ends of the cylinders. A scraper (not shown) may be employed to ride in each of the grooves 51 to remove any fibers or other foreign matter so that effective registration may be had between the edges of the seals 50 and grooves 51.

It is to be emphasized, as heretofore pointed out, that the thickness of the board being made is controlled entirely by regulating the consistency and amount of stock, all of which is controlled at the head box 6 relative to the speed of rotation of the forming cylinders. The hydrostatic head forcing liquid to the so-called upper inlet 47 is always slightly greater than the hydrostatic head forcing the pulp suspension to the lower inlet so that there will be proper balancing of pressure within the forming chamber, i. e., so that none of the pulp suspension discharging through the mouth 28 will back up through the mouth 49.

As a feature of the invention, attention is

to be directed to the fact that the felting cylinders are so arranged as to rotate for a limited portion of their travel only in the forming chamber, in the present instance materially less than one-half. I have found it to be a distinct disadvantage in the formation of a relatively thick board of the character made on the present machine to have any large portion of the forming cylinders submerged at any one time, due to the fact that water continuously dropping off from the forming cylinder has a tendency to flow back down on the sheet being formed, causing variations in the thickness and re-floating of the individual fibers in water. As a matter of fact, in the present invention the two cylinders 29 and 29' are mounted over the forming chamber 27 in such a manner that the center of the forming chamber coincides with and is directly below, the nip where the sheets carried by the two cylinders come together. While I have shown two chambers 22, it is obvious that I may use one or more. I have found that two can be efficiently used with a machine having cylinders approximately thirteen feet in length and 60" or larger in diameter.

The amount of water contained in the board after it is stripped from the lower forming cylinder is regulated entirely by the pressure applied by the two forming cylinders against the board through the medium of the compression coil spring 60. Normally, the two forming cylinders are separated about $\frac{1}{8}$ " to $\frac{1}{2}$ " when no pulp is passing between them, this separation being brought about by any type of adjustable stop, preferably an adjustable bolt 55. When pulp is passing between the two forming cylinders in the formation of a sheet, the movable cylinder gives, and the tension of the spring provides proper pressure to remove the desired amount of water from the felted board.

As the board 54 leaves the forming cylinder 29', the thickness thereof may be determined in any conventional manner, for instance, through the medium of a visual device, comprising a roller contacting with the wet fiber board as it leaves the forming cylinder, which roller actuates a diaphragm to raise or lower a column of colored liquid in a suitable glass tube which can be observed by the operator. It is to be understood that any device for effectively determining the thickness of the board leaving the forming cylinder 29' may be employed. The cylinder 29' is disposed on a lower plane (about 4", more or less) relative to cylinder 29 so that the board 54 will be carried on the cylinder 29' to the belt 46. The cylinders preferably are of the same diameter.

As a feature of the invention it is to be noted that the stock is fed upwardly and collected on the forming cylinders while they are both moving upwardly, as distinguished

from those machines and processes in which the pulp is fed downwardly, or horizontally, and collects on the surface of the forming cylinders while the latter are moving downwardly or in a horizontal plane. It has always been difficult in the operation of the type of machine of the present invention to secure a perfect seal between the ends of the two cylinders and the ends of the forming chamber. This seal is accomplished in the present invention in a very effective and economical manner, and while it is stationary, it functions perfectly in all positions of the two cylinders within any range of practical use.

While I have designated cylinder bearing 37 as being stationary and cylinder bearing 37' as being movable, it is obvious that this is just for purposes of illustration. The bearings of either cylinder may be made stationary, and correspondingly the bearings of either cylinder may be made movable. It may be found to be of advantage to make the cylinder 29 the movable cylinder rather than the cylinder 29'.

I have found that the design of the forming chamber 27 is of importance in that its shape has very much to do with the successful formation of a heavy sheet of fibrous board. Its cross-sectional area, as shown in Fig. 5, should be proportioned in exact relation to the speed at which the sheet of board is formed.

Cross reference is made to my co-pending application 304,255 wherein the novel sealing means herein described, is reserved and claimed.

I claim as my invention:

1. A machine comprising in combination forming cylinders geared together to rotate in unison, a forming chamber disposed below said forming cylinders substantially centrally of the bite between, and communicating with, said forming cylinders, a seal disposed adjacent the sides of the forming cylinder for preventing leakage past the sides of the forming cylinder and the forming chamber and separate inlets for supplying water and pulp to said forming chamber, one disposed adjacent the lower end thereof and the other disposed above said lower inlet.

2. A machine comprising in combination, forming cylinders geared together to rotate in unison, a forming chamber disposed below said forming cylinders substantially centrally of the bite between and communicating with, said forming cylinders, a seal disposed adjacent the sides of the forming cylinder for preventing leakage past the sides of the forming cylinder and the forming chamber and separate inlets for supplying water and pulp to said forming chamber, one disposed adjacent the lower end thereof and the other disposed above said lower inlet, the discharge from the lower inlet to the forming chamber

being disposed centrally below the point at which the sheets carried by said cylinders come together.

3. A machine comprising in combination, forming cylinders geared together to rotate in unison, a forming chamber disposed below said forming cylinders substantially centrally of the bite between and communicating with, said forming cylinders, a seal disposed adjacent the sides of the forming cylinder for preventing leakage past the sides of the forming cylinder and the forming chamber and separate inlets for supplying water and pulp to said forming chamber, one disposed adjacent the lower end thereof and the other disposed above said lower inlet, the discharge from the lower inlet to the forming chamber being disposed centrally below the point at which the sheets carried by said cylinders come together, and the discharge from said upper inlet to the forming chamber being disposed in the same vertical plane as the discharge from said lower inlet.

4. A machine comprising in combination, forming cylinders geared together to rotate in unison, a forming chamber disposed below said forming cylinders substantially centrally of the bite between and communicating with said forming cylinders, a seal disposed adjacent the sides of the forming cylinder for preventing leakage past the sides of the forming cylinder and the forming chamber and separate inlets for supplying water and pulp to said forming chamber, one disposed adjacent the lower end thereof and the other disposed above said lower inlet, means for charging the lower inlet with pulp suspension and separate means, independently controlled, for charging said upper inlet.

5. A machine comprising in combination, forming cylinders geared together to rotate in unison, a forming chamber disposed below said forming cylinders substantially centrally of the bite between and communicating with said forming cylinders, a seal disposed adjacent the sides of the forming cylinder for preventing leakage past the sides of the forming cylinder and the forming chamber and separate inlets for supplying water and pulp to said forming chamber, one disposed adjacent the lower end thereof and the other disposed above said lower inlet, the discharge from the lower inlet to the forming chamber being disposed centrally below the point at which the sheets carried by said cylinders come together, the discharge from said upper inlet to the forming chamber being disposed in the same vertical plane as the discharge from said lower inlet and immediately adjacent the point at which the sheets carried by said cylinders come together.

6. A process of forming a relatively thick felted fiber board, which comprises maintaining a hydrostatic pressure on pulp sus-

quantities of same to a felting instrumentality to cause two sheets to be simultaneously formed, thereafter uniting said sheets while still wet to produce a single sheet, and immediately adjacent the point at which said sheets are united introducing a regulated quantity of water to cause a mild disturbance at that point.

7. A process of forming a relatively thick felted fiber board, which comprises maintaining a hydrostatic pressure on pulp suspension, continuously feeding regulated quantities of same to a felting instrumentality to cause two sheets to be simultaneously formed, thereafter uniting said sheets while still wet to produce a single sheet, and immediately adjacent the point at which said sheets are united introducing a regulated quantity of water to cause a mild disturbance at that point, said process being characterized in that the major quantity of pulp is fed to said felting instrumentality at a point materially below the point at which said water is introduced.

8. A machine comprising in combination, a forming chamber, an inlet for pulp suspension at the lower portion of said chamber, said chamber having side walls which diverge upwardly away from said inlet on opposite sides thereof and which terminate intermediate the height of said chamber, and a pair of forming cylinders adapted to rotate in unison through the portion of said chamber above the upper ends of said walls and in close proximity to said ends.

9. A machine comprising in combination, a forming chamber, an inlet for pulp suspension at the lower portion of said chamber, said chamber having side walls which diverge upwardly away from said inlet on opposite sides thereof and which terminate intermediate the height of said chamber, means for introducing water to said chamber at a point above said inlet, and a pair of forming cylinders adapted to rotate in unison through the portion of said chamber above the upper ends of said walls and in close proximity to said ends.

In testimony whereof I affix my signature.
EDWARD S. SHEPERD.
